TABLE

Robert D. Cook, 16931 Marquez Ave.,
Pacific Palisades, Calif.

Filed Feb. 3, 1961, Ser. No. 63,817

Term of patent 3½ years

(Cl. D33—14)

FIG. 1.

FIG. 2.

FIG. 3.

FIG. 4.

FIG. 5.

The dominant portions of the design reside in the solid line showings.

I claim:

The ornamental design for a table, substantially as shown and described.
